ROBERT C. GIBBONS AND THEODORE K. FELCH, OF JERSEY CITY, NEW JERSEY.

SMOKING PIPE.

Application filed February 24, 1920. Serial No. 360,718.

To all whom it may concern:

Be it known that we, ROBERT C. GIBBONS and THEODORE K. FELCH, citizens of the United States, and residents of the city of Jersey City, in the county of Hudson, State of New Jersey, have invented certain new and useful Improvements in Smoking Pipes, of which the following is a specification.

The improvements relate more particularly to the stem of the pipe, and have for their objects, among others, the provision of a stem which may be made of any suitable material and which will not clog with tobacco from the bowl, products of combustion or saliva, will condense and retain moisture and oil from the tobacco and smoke and hold it in such a manner that it will not be drawn into the mouth, will trap and separate saliva from the other substances, maintain a dry bowl, will separate the smoke from matter passing with it from the bowl and cool and purify the smoke, and which may be quickly and easily separated from the bowl and cleaned.

The improvements are illustrated in the accompanying drawings, in which Figure 1 is a vertical medial section taken longitudinally of a pipe embodying the improvements; Figure 2 is a plan and side elevation partly in section of the removable condenser and separator enlarged; Figure 3 are top and bottom plans and side elevation partly in medial cross-section of the middle removable portion of the stem with the parts shown in Figure 2 removed.

The pipe consists essentially of four sections, viz: the bowl A, the middle section B, the condenser and strainer or percolator C, the part B carrying the strainer and the tube E.

The bowl proper A is of usual form, but may be varied as desired, and the smoke channel F, leading from the bowl cavity, is formed in the usual manner. The neck G of the bowl is bored out to form a chamber for the reception of smoke from the bowl, constituting a trap for small particles of tobacco or other substances and oil and water, or other liquids condensed from the smoke. The outer part is stepped, as shown at H, to receive the reduced portion B' of the middle section B. This part may be reinforced by a metallic collar J.

The lower reduced part of the middle section has an enlarged bore, and the upper

part of this section has a still larger bore, the former to receive the part C and the latter to receive the stepped end D' of the stem. The stem also has a large bore D² at its lower part terminating in the small channel D³ and extending thence through the mouth piece D⁴. This enlarged bore may have a shoulder at its upper end, as shown at D⁵, and this is of advantage, particularly where straight stems are used in preventing liquid from passing up through the mouth piece.

The strainer and condenser C has a conical portion C' pointed toward the smoke channel, leading from the bowl and located in the trap G. At the base of this cone is an annular flange C² projecting beyond the said base and being slightly less than the diameter of the trap G. A deep annular groove C³ separates this flange from the thicker flange C⁴, of substantially the same diameter as the flange C², and extending through this flange are a series of small perforations C⁵. The part C is preferably made of a single piece of metal, but may be made of any desired substance and in parts if desired. It is held in the lower end of the bore of the middle section B by means of the flange C⁴ which fits snugly therein. By this construction and arrangement the smoke passing from the bowl is caused to strike the conical portion of the part C and then to pass up around the edges of the flange C², through the groove C³ and through the perforations C⁵, thus condensing moisture and oil in the smoke, cooling the same to a certain extent and permitting condensed liquid to pass over the cone and drop into the trap G. At the same time solid particles are prevented from passing with the smoke into the upper part of the stem.

The tube E is fitted into the narrow middle portion B² of the middle section and extends therefrom upwardly, projecting into the enlarged bore D² of the stem. Between its lower or inner end and the flange C⁴ is a chamber B³, which will serve to catch any liquid or solid matter carried along with the smoke that passes the part C. This tube E fits the bore of the middle section so that smoke must pass through it to the stem, and as it is pointed upwardly to approximate the form of a nozzle the velocity of the smoke passing through it will be somewhat increased and condensed. On issuing into the

chamber D², however, it will expand again before passing into the bore extending through the mouth piece.

When it is desired to clean the pipe it is only necessary to remove the stem D from the middle section B to eliminate liquid that may have accumulated therein—which cannot pass down into the parts below the stem—and to remove the middle section from the shank of the bowl and clean out the trap. The part C and the chamber above it may also be cleaned by removing this part if desired. Any one or more of these cleaning operations may be performed as desired, the middle section being separated from the other parts or remaining secured to the stem or the bowl.

What we claim is:

1. A pipe comprising a bowl having a restricted outlet, a stem made in separable sections and having a continuous channel extending therethrough and in communication with said outlet, said channel having an enlargement adjacent the outlet and an enlargement removed therefrom and toward the outer end of the stem, a removable baffle between said enlargements having an imperforate conical portion pointed toward said outlet, so constructed and arranged as to permit the passage of smoke and other combustion products between the walls of the pipe and the base of the conical portion, a diaphragm portion connected with said conical portion spanning the bore of the channel, said diaphragm having restricted passages therethrough between which and the outlet the conical portion is interposed, and a member outward of said baffle extending into the outer enlargement and beyond the lower portion of the same having a passage way communicating with said diaphragm passages and said last named enlargement, there being a chamber of greater diameter and capacity than the said diaphragm openings and the last named passage.

ing into the outer enlargement and beyond the lower portion of the same having a passage way communicating with said diaphragm passages and said last named enlargement.

2. A pipe comprising a bowl having a restricted outlet, a stem made in separable sections and having a continuous channel extending therethrough and in communication with said outlet, said channel having an enlargement adjacent the outlet and an enlargement removed therefrom and toward the outer end of the stem, a removable baffle between said enlargements having an imperforate conical portion pointed toward said outlet, so constructed and arranged as to permit the passage of smoke and other combustion products between the walls of the pipe and the base of the conical portion, a diaphragm portion connected with said conical portion spanning the bore of the channel, said diaphragm having restricted passages therethrough between which and the outlet the conical portion is interposed, and a member outward of said baffle extending into the outer enlargement and beyond the lower portion of the same having a passage way communicating with said diaphragm passages and said last named enlargement, there being a chamber of greater diameter and capacity than the said diaphragm openings and the last named passage.

Witness our hands this 15 day of January, 1920, at the city of New York, in the county and State of New York.

ROBT. C. GIBBONS.
THEODORE K. FELCH.
